UNITED STATES PATENT OFFICE.

ALLAN S. BIXBY, OF INDIANAPOLIS, INDIANA, ASSIGNOR TO THE NATIONAL
MALLEABLE CASTINGS COMPANY, OF CLEVELAND, OHIO, A CORPORATION OF
OHIO.

MOLDING-MACHINE.

1,327,419.

Specification of Letters Patent.

Patented Jan. 6, 1920.

Application filed July 27, 1915. Serial No. 42,168.

To all whom it may concern:

Be it known that I, ALLAN S. BIXBY, a citizen of the United States, and a resident of Indianapolis, in the county of Marion and State of Indiana, have invented new and useful Improvements in Molding-Machines, of which the following is a specification, reference being had to the accompanying drawings, in which—

10 Figure 1 is a front elevation, partly in section, of a molding machine embodying my invention; Fig. 2 is a side elevation thereof; Fig. 3 is a section of the cylinders comprising operating mechanism; Fig. 4 is a section 15 of the mechanism shown in Fig. 3, but in a different operative relation; Fig. 5 is a detail of the valve in the supplementary piston; Fig. 6 is a detail of the valve operating plunger, Fig. 7 is a detail of the bail centering member, and Fig. 8 shows a detail of the cylinder heads with a cylinder case of different dimensions shown in Figs. 1, 2 and 3, secured therein.

My invention relates to power molding machines, and consists in a slidably mounted table for the molds, so actuated that it will pack the molding material in the mold while the mold is being filled, and after the mold has been filled will squeeze the mold 25 and thereby compress the molding material therein. My invention also consists in mechanism whereby various sizes of pressure cylinders may be used merely by changing the case and contained parts, but without changing the cylinder heads. My invention also consists in the construction and coöperation of the various parts which I shall hereinafter describe and claim.

Referring to the drawings, the machine 40 has two cylinder heads 2 and 3, which have at each end recesses 4 for reception of sleeves 5, which may be secured in the recesses by Babbitt metal or any other suitable means. The lower cylinder head 2 is supported on 45 struts 6, which, if it is desired to have the machine movable from place to place, may be mounted on wheels 7. The struts 6 also support a shaft 8, which extends beneath the head 2 and seats in bearings 8' in the

ends of the head 2. Rotatably mounted on 50 the ends of the shaft 8 are bail rod bearings 9, which carry the lower ends of the bail rods 10. On the upper end of the rods 10 is secured the bail 11, the height of which may be adjusted on the rods 10 by the 55 nuts 11'.

The cylinder case 12 seats in grooves 13 and 14 respectively, in the upper and lower heads 2 and 3. I have shown in Fig. 8 each head having a number of grooves, so that 60 each head is capable of use with casings and pistons of various sizes. After the case 12 has been put in position between the upper and lower heads 2 and 3 they are bolted together and the sleeves 5 are applied. 65

The table 15, which is mounted on, but not secured to, the inner or supplementary piston B, has on each end guide rods 16, which reciprocate through the openings in the upper head 3 and the sleeves 5, and extend in lowermost position into the recesses 4 in the lower head 2. 70

Air for the main cylinder is admitted through the valve 17, and is tapped directly into the bottom of the main cylinder 75 through the inlet 17', and is exhausted through the same inlet 17' and valve 17. Two openings 18 are arranged in the upper part of the case 12, through which air above the main piston A escapes in squeezing, and 80 through which air enters as the main piston is retracted. Air for the jarring operation is controlled by the valve 19 and is tapped into the supplemental cylinder B through the inlet 19'. 85

The device is operated as follows:

The operator, when the device is first used, has placed the mold case or flask C on the table 15 above the secondary piston B. The valve 19 is opened and the air passes through 90 the inlet 19' into the chamber 20 in the piston B as is shown in Fig. 3. In the chamber 20 is positioned a valve 21, which has channels 22 in the sides of its head and rod 23, thus permitting the passage of air when 95 the valve is raised from its seat 24, down into the chamber 25 between the pistons A and B, thus raising the piston B. At the

- same time the air passes through the duct 26 down into the chamber 27 and raises the plunger 28. The plunger 28 has a stem 29, intended to engage the lower end of the 5 valve rod 23. The plunger 28 is lifted by the air in the chamber 27 and keeps in contact with the rod 23, holding it off its seat 24 and permitting the air to continue to enter into the chamber 25.
- 10 As the air continues to enter the chamber 27 the plunger 28 will rise, following the rod 23, until its shoulder 30 strikes the stop 31, and thereafter, as the supplementary piston B continues in its upward movement, 15 the rod 23 will remain stationary and the seat 24 on the supplementary piston B will come into contact with the valve 21, closing the air passage and cutting off the air supply. The air in the chamber 25 continues 20 to expand and to lift the supplementary piston B with its load, thus carrying the rod 23 away from the upper end of the stem 29, thereby opening the duct 32 in the stem 29 and permitting the air to escape through the 25 duct 33 into the primary cylinder chamber 34. The force of the outrushing air will assist in driving down the plunger 28, the air from the chamber 27 escaping through the duct 26, through which it entered into 30 the chamber 25. To make the return or downward movement of the plunger reliable and positive, I, however, prefer to employ a spring 28', interposed between the plunger and the stop or shoulder 31, which is strong 35 enough to force the plunger downward when the air pressure is relieved.
- When the pressure is relieved the supplemental piston B drops down, striking the shoulder 35, thus jarring down the sand in 40 the mold. As the supplementary piston B drops down, carrying with it the valve rod 23, its lower end again comes into contact with the stem 29, as is shown in Fig. 4, which keeps it from dropping with the supplemental piston B, thus unseating the 45 valve 21 and permitting the air to again enter through the channels 22 in the sides of the valve 21 and its rod 23 into the chamber 25.
- 50 The cycle of operations is again and again repeated until the mold is filled and the sand has been packed or jarred down firmly into place.
- When the mold has been filled, as just described, the operator places the cover on the 55 top of the mold and then pulls the bail 11 over into vertical alinement with the mold table 15. He then opens the valve 17, admitting air into the primary cylinder chamber 60 24, which lifts the piston A and with it the supplementary cylinder B and the mold C, and squeezes the mold against the bail 11. When sufficient pressure has been applied in this manner the valve 17 is turned 65 to exhaust position and the air in the lower

part of the primary cylinder chamber is exhausted, permitting the main piston A to retract or descend, and with it the mold table and mold. The bail 11 is then swung to one side and the mold may then be removed. 70

The bail 11 is held in a vertical position by a centering member 36, preferably rectangular in form, which at one end is secured to the frame of the machine and at 75 its other end 39 seats in a recess 37 of the spring 38 attached to a bail rod 10. The bail 11 can be swung to one side, as is shown in dotted lines in Fig. 2, only to the extent provided for by the aperture in the member 36 through which the bail rod 10 extends. 80

The terms and expressions which I have employed are used as terms of description and not of limitation, and I have no intention, in the use of such terms and expressions, of excluding any mechanical equivalent for the features shown and described, but recognize that various modifications are possible within the scope of the invention 90 claimed. 95

What I claim is:

1. In a power molding machine, cylinder heads adapted for securing therein differently dimensioned cylinder cases and being 95 also adapted to contain differently dimensioned operating parts, and a movable mold table guided by at least one of said cylinder heads and actuated and supported by the operating parts. 100

2. In a molding machine, a cylinder, a fluid actuated piston within said cylinder, a valve mounted in one of said members and movable therewith, a plunger in the other of said members having a valve seat thereon, 105 said valve seat normally holding the valve in open position, the plunger being moved by fluid pressure so that the valve seat follows the valve for a portion of the stroke of the piston, the valve moving away from the valve seat during the remainder of the stroke of the piston allowing the valve to close, and providing an outlet for the actuating fluid. 110

3. In a power molding machine, a movable mold table mounted on a piston, said piston being positioned in a chamber in a second piston, said second piston being seated in a cylinder, an air inlet through the first-mentioned piston into the chamber in 120 the second mentioned piston, a valve in said inlet, and a plunger mounted in said second mentioned piston adapted to unseat the valve in said inlet and thereby admit air. 115

4. In a power molding machine, upper 125 and lower cylinder heads, a plurality of oppositely disposed sets of recesses in said cylinder heads adapted to receive differently dimensioned cylinder cases.

5. In a molding machine, a cylinder, a 130

fluid actuated piston within said cylinder, a valve mounted in one of said members and movable therewith, a plunger in the other of said members engaging a stem on the valve to hold the valve normally in open position, the plunger being moved by fluid pressure to follow the valve during a por-

tion of the stroke of the piston, the valve moving away from the plunger during the remainder of the stroke, thereby uncovering 10 an outlet for the actuating fluid between the members.

ALLAN S. BIXBY.
